CLAIM

The ornamental design for an icon font or the like, as shown and described:

DESCRIPTION

FIG. 1 is a face view of an icon front or the like showing our new design in display position;

FIG. 2 is a face view of the icon font alone shown on an enlarged scale.

The broken line showing of a half tone display screen in FIG. 1 is for illustrative purposes only and forms no part of the claimed design.

FIG. 1

FIG. 2
